UNITED STATES PATENT OFFICE.

ALBERT P. LEE, OF CHICAGO, ILLINOIS.

MOVABLE LOADING-HOPPER.

1,212,368.

Specification of Letters Patent. Patented Jan. 16, 1917.

Original application filed January 8, 1914, Serial No. 810,964. Divided and this application filed May 4, 1914. Serial No. 836,152.

To all whom it may concern:

Be it known that I, ALBERT P. LEE, a citizen of the United States, residing at Chicago, in the county of Cook and State of Illinois, have invented a certain new and useful Improvement in Movable Loading-Hoppers, of which the following is a full, clear, concise, and exact description, reference being had to the accompanying drawings, forming a part of this specification.

My invention relates to movable loading hoppers and has for its object the provision of a new and improved device capable of use for loading and unloading.

My invention in one of its forms contemplates the provision of a suitable framework adapted to support a hopper movable upon said framework from a loading to an unloading position.

My application herein is a divisional application of a prior application Serial No. 810,964, filed Jan. 8, 1914.

My invention contemplates also the provision of a hopper of unbalanced construction, the purposes of which will appear hereinafter.

My invention also contemplates means whereby after the hopper has been moved to its unloading position it may be slightly elevated to withdraw the snout of the hopper from the deposited material.

I will explain my invention more in detail by referring to the accompanying drawings illustrating the same in which—

Figure 1 is an end view of the structure illustrating features of my invention as applied to a stationary device; Fig. 2 is a side view of the structure illustrated in Fig. 1; Fig. 3 is an enlarged view of a detail of construction along line b—b of Fig. 1, and Fig. 4 is a detail perspective view of the hopper elevating arm.

In general my improved device consists of a preferably collapsible framework which may be set up between a bin or device from which material is to be unloaded and a wagon or other receptacle into which the material is to be deposited. The framework carries a hopper which rolls upon this framework from one limiting position to the other, the arrangement being such that the hopper 1 as shown in the illustration may occupy the position 26 when in its receiving position, and occupy the position shown in

full lines in Fig. 1 when in its discharge position. The hopper is unsymmetrically arranged so that it is necessary to hold the hopper in its loading position so that when it is released it will roll automatically into the discharge position. Means are then provided to slightly elevate the hopper from its discharge position to withdraw it from the discharged material, if that is necessary, through the agency of instrumentalities which will be presently explained.

Referring to the illustrations I show the hopper 1 as suitably operating upon rails 3, 4. These rails however are carried by a collapsible framework consisting of the bars 5, 6, 7 and 8. These bars are united by a suitable shaft 9 and are held in position through suitable chains 10 and 11. The hopper is provided with chains 12, 12, to be held in position by a finger 13. This finger is pivotally carried by a handle 14 held in a suitable catch 15 and released at will, as is clearly evident from the illustration to either hold the hopper in its limiting position or to permit its release. The hopper is provided with pins 16 adapted to engage a finger 17, which finger is carried by a bell crank lever pivoted at 18.

When the hopper and other parts are in the position shown by the full lines of Fig. 1, it will be seen that it has just deposited its contents. Now it may be that the snout of this hopper upon discharging the material still projects into the discharged material. In order to clear the snout of the hopper without having some of this discharged material fall back into the hopper, I rotate the lever 19 in a clockwise direction (Fig. 1) through the agency of the chain 20, which may be rolled upon the drum 21. This drum is rotated through the agency of the ratchet wheel 22 which it carries and the associated pawl 23 under the control of the operating arm 24. A suitable retaining pawl 25 is provided to hold the drum in a given position until this pawl 25 is released to permit the bell crank lever to again occupy the position shown in full lines in Fig. 1. Suitable chains 23 prevent the hopper in connection with the pin 16 from leaving the rails when discharging. The dotted position of the hopper shown at 26 in Fig. 1 indicates the loading position of the hopper of this structure.

The hopper 1 is provided with suitable channels so that it may properly ride upon the rails.

From what has been described it is thought the nature of this stationary loading mechanism will also be apparent.

Bins 28 and 29 are provided, the bin 29 being the bin from which material is to be discharged into the bin 28, material being shoveled from bin 29 into the hopper, then conveyed by the hopper, and dumped into the bin 28.

Having however thus described my invention, it will be clear that it is susceptible of many and various modifications without departing from its spirit.

Having however thus described one form which my invention may take, what I claim as new and desire to secure by Letters Patent is:

1. A device of the character described comprising a hopper carrying framework, a hopper adapted to roll on said framework from one limiting position to the other, and means adapted when said hopper is in a limiting position to elevate said hopper to withdraw a projecting portion of said hopper from discharged material, said means including a pin provided upon said hopper,

and a pivotally mounted finger carried by said framework.

2. A device of the character described comprising a hopper carrying framework, a hopper adapted to roll on said framework from one limiting position to the other, and means adapted when said hopper is in a limiting position to elevate said hopper to withdraw a projecting portion of said hopper from discharged material, said means including a pin provided upon said hopper, a pivotally mounted finger carried by said framework, and a pawl and ratchet mechanism for operating said finger.

3. A device of the character described comprising a hopper carrying framework, a hopper adapted to roll on said framework from one limiting position to the other, and means adapted when said hopper is in a limiting position to elevate said hopper relative to said framework to thereby withdraw a projecting portion of said hopper from discharged material.

In witness whereof, I hereunto subscribe my name this 22nd day of April, A. D., 1914.

ALBERT P. LEE.
